UNITED STATES PATENT OFFICE.

EDWARD R. NICHOLS, OF BRIDGEPORT, CONNECTICUT.

KNIFE SHARPENER.

Application filed July 12, 1921. Serial No. 484,063.

To all whom it may concern:

Be it known that I, EDWARD R. NICHOLS, a citizen of the United States, residing at Bridgeport, in the county of Fairfield and State of Connecticut, have invented certain new and useful Improvements in a Knife Sharpener, of which the following is a specification.

This invention relates to sharpeners for 10 knife blades and the like, and the object thereof is to provide a simple and inexpensive device of this character capable of readily sharpening knives and adapted to hold the blades in proper position in order 15 that an inexperienced person may accurately sharpen a knife thereon.

With these and other objects in view, the invention consists in certain novel features of construction as hereinafter shown, described and claimed.

In the accompanying drawings:

Figure 1 represents a front elevation of a knife sharpener constructed in accordance with this invention, with a knife blade 25 shown in operative position relative thereto.

Fig. 2 is a vertical section taken on the line 2—2 of Fig. 1.

Fig. 3 is a transverse section taken on the line 3—3 of Fig. 2.

Fig. 4 is a front view with the sharpening tool removed.

Fig. 5 is a rear elevation with the tool removed.

Fig. 6 is a detail vertical section taken 35 on the line 6—6 of Fig. 4.

Fig. 7 is a transverse section taken on the line 7—7 of Fig. 4; and

Fig. 8 is a similar view taken on line 8—8 of Fig. 4.

In the embodiment illustrated the sharpener constituting this invention comprises combined supporting base and attaching means in the form of oppositely extending apertured feet 1 and 2, designed to be 45 mounted on a suitable support, such as a table top, bench, or against the wall, and held engaged therewith by screws passing through the apertures in said feet.

A standard 3 rises from the base, and is 50 bifurcated at its upper end, with the furcations 4 and 5 thereof flared, as is shown clearly in Fig. 1, and the standard 3 has its outer face provided with a substantially V-shaped vertically disposed groove or seat 7 55 extending from the base of said furcations to the bottom of the standard and in which

is adjustably secured a sharpening tool 6. This tool 6 is lengthwise adjustable on the seat 7 and corresponds in shape thereto, as shown triangular in cross section. A 60 laterally projecting and outwardly bowed tool guide 8 is formed integral with the standard 3, intermediate its ends, and between said guide 8 and the walls of seat 7, the tool 6 is held in position by a securing wedge 9, 65 as shown clearly in Figs. 2 and 3.

The sharpening tool 6 is made equilateral triangular in cross section so that the faces thereof against which the knife blade B is sharpened, may be changed when one is 70 worn or when it is desired to change the knife engaging surface of the tool for any purpose.

In the use of the sharpener, the attaching feet 1 and 2 are connected with a suitable 75 support to hold the device rigid, and then the sharpening tool 6, which is preferably constructed of hard steel, although it may be made of any suitable material, is inserted in the seat 7 and secured in the desired position therein by means of the wedge 9. The tool is then ready for use, and a blade B to be sharpened is drawn through the space between one face of the tool 6 and one of the furcations 4 or 5, as is shown clearly in Fig. 85 1, so that opposite sides of the blade are sharpened correspondingly.

The preferred embodiment of the invention is disclosed in the drawings and set forth in the specification, but it will be understood that any modifications within the scope of the claimed invention may be made in the construction without departing from the principle of the invention or sacrificing any of its advantages.

What I claim is:

1. A knife sharpener comprising a standard formed with a V-shaped opening at its upper end and further having its outer face provided with a vertical V-shaped seat depending from the bottom of the opening, a laterally projecting and outwardly bowed tool guide integral with the outer face of the standard and opposing said seat, a triangular shaped sharpening element mounted 100 on said seat and projecting into said opening and having its projecting end opposed by the walls of the opening, a securing element interposed between the guide and the sharpening element, and oppositely extending apertured feet integral with the lower end of the standard.

2. A knife sharpener comprising a standard having its upper portion formed with a V-shaped opening and having its outer face provided with a vertical V-shaped seat depending from the bottom of the opening and extending to the lower end of the standard, a laterally projecting and outwardly bowed tool guide integral with the outer face of the standard and opposing said seat, a sharpening element of equilateral contour mounted on the seat and projecting into

said opening and having the projected portion thereof opened by the walls of the opening, said element being lengthwise adjustable on its seat, a wedge shaped securing element interposed between the guide and the sharpening element, and oppositely extending apertured feet integral with the lower end of the standard. 15

In testimony whereof, I affix my signature hereto.

EDWARD R. NICHOLS.
